UNITED STATES PATENT OFFICE

GLENN T. GOURLEY, OF YOUNGSTOWN, OHIO, ASSIGNOR TO GENERAL FIREPROOFING COMPANY, OF YOUNGSTOWN, OHIO, A CORPORATION OF OHIO

WALL CABINET STRUCTURE

Application filed March 2, 1929. Serial No. 344,032.

This invention relates to improvements in cabinets of the type which are inclusive of a casing and a finishing frame, the purpose being to provide means to assure a tight fit 5 of the casing within the finishing frame irrespective of variations in size, within liberal manufacturing tolerance limits, of either or both the casing and the frame.

In particular the invention relates to metallic wall cabinets of the built-in type, that 10 is, to cabinets of the type in which a casing is adapted to be mounted within a frame built into or otherwise rigidly and to all intents and purposes, permanently attached to 15 a wall in finishing relation to a casing receiving opening or recess formed therein. Specifically, therefore, it is the purpose of the present invention to provide a finishing frame with means whereby it is adapted to be 20 built into or otherwise permanently secured to a wall to receive a casing, and to so construct the frame and casing that when the casing is engaged in the frame marginal portions 25 of the casing will fit tightly within the frame despite a possible difference in size, within liberal manufacturing tolerance limits, between the frame and the casing.

Another purpose of the invention is to so 30 construct a cabinet frame and casing that the casing will become tightly fitted within the frame as the result of the mere act of pushing the casing into the frame.

A further purpose of the invention resides 35 in the provision of means to enable the casing readily to be secured in the frame and as readily detached and removed therefrom.

With the foregoing and other purposes in view the invention consists in the novel features of construction, combination and arrangement of parts as will be hereinafter more fully described, illustrated in the accompanying drawings and defined in the appended claims.

In the drawings, wherein like characters 45 of reference denote corresponding parts in the different views:

Fig. 1 is a front elevation illustrating the improved cabinet construction.

Fig. 2 is a horizontal section on the line 50 2—2 of Fig. 1.

Fig. 3 is an enlarged front elevation of a section of the frame element; and

Fig. 4 is a perspective view of one of the frame anchoring elements.

Referring now to the drawings in detail, it 55 will be observed that the present cabinet structure includes essentially a frame element A and a casing element B.

Frame element A, which may be of any suitable or desired shape, is illustrated in the 60 present instance as comprising spaced side rails 10—10 and a connecting top rail 11, the lower ends of the side rails resting upon the floor or other foundation 12 and being otherwise unconnected with one another. If desired, however, the bottom portions of the 65 sides 10 may be connected in the same manner as their top portions by means of a transverse rail in all respects a duplicate of top rail 11. Whatever shape the frame may be, all of the 70 rail portions thereof are of corresponding cross-section, and as best illustrated in Fig. 2 each of said rail portions in cross-section consists of a front portion 13, a side portion 14 and a rearwardly and inwardly directing 75 connecting portion 15 disposed at obtuse angles to the portions 13 and 14, which latter are disposed at right angles to one another. The marginal portions 16 and 17 of the portions 13 and 14, respectively, are bent 80 to extend inwardly towards one another and are disposed at acute angles to the portions 13 and 14, respectively, while U-shaped slits are cut in the portion 15 at suitable intervals to provide tongues 18 which are bent outward to lie parallel or substantially parallel 85 to the side portion 14.

Casing element B which corresponds in shape to frame A and which is adapted to be received in the latter, consists in the present instance of side portions 19 and a connecting top portion 20, each of uniform cross-section. Should frame A be provided with a bottom rail, said casing would be provided with a cooperating bottom portion as is understood. As previously intimated casing B is adapted to be fitted tightly within the frame A by the mere act of pushing the casing into the frame and to this end said casing is constructed to include a marginal portion 100

laterally offset outwardly with respect to the body portion thereof for cooperation with the inclined portions 15 of the respective rail portions of frame A. In other words, casing B consists in cross-section of a body portion 21 adapted to extend parallel to the portion 14 of the frame A when the casing is engaged in said frame, and a laterally outwardly directed front portion 22, the marginal portion 23 of which extends inwardly at an acute angle to said portion 22 for engagement with the portion 15 of frame A. Thus, even though there be a material difference in size between the frame A and casing B, portion 23 will, as the result of the mere act of pushing the casing into the frame, contact tightly with the portion 15 due to the angular disposition of the latter with respect to the direction of movement of the casing into the frame, it being understood, of course, that the portions 15 of the respective rails of the frame cooperate with one another to produce an inwardly tapering frame mouth assuring contact of all of the casing portions 23 therewith and also centering of the casing within the frame.

After the casing has been pushed into the frame a sufficient distance to bring the portions 23 into firm contact with the portions 15, screws or other suitable fasteners 24 are adapted to be passed through the casing into the tongues 18 to secure the casing and the frame together. To this end portions of the sides 21 of the casing preferably are offset laterally as indicated at 25 to lie against the tongues 18 when the casing is engaged within the frame, these portions 25 being provided either initially, or after assembly of the casing and frame, with fastener receiving openings, and cooperating fastener receiving openings in the tongues 18 being formed preferably after assembly of the casing with the frame, it being noted in this respect that the portions 25 do not shift laterally but only fore and aft with respect to the tongues 18 during fitting of the casing within the frame.

Frame A is adapted to be built into or otherwise permanently assembled or connected with a wall in finishing relation to a casing receiving opening or recess formed therein and to this end a plurality of frame anchoring elements C are provided as illustrated in detail in Fig. 4 of the drawings. These anchoring elements consist in the present instance of corrugated plates 26 adapted to be embedded in the masonry of the wall, said plates having formed thereon or rigidly attached thereto in any suitable manner bars 27 shaped at their ends to be snugly received within the acute angular portions of the frame formed between the portions 13-16 and 14-17 thereof, respectively, for locking the frame to said anchoring elements, angle iron pieces 28 preferably but not neces-

sarily being provided to reinforce said anchoring elements.

From the foregoing description considered in connection with the accompanying drawings it is believed that the construction, operation and advantages of the present improved cabinet structure will be clearly understood. It is desired to point out however that various changes and desirable additions may be made in and to the structure shown within the spirit and scope of the invention as defined in the appended claims.

I claim:

1. A cabinet comprising a frame, a casing for engagement within said frame, and rearwardly and inwardly directed surfaces on said frame and casing, respectively, coacting to produce a tight fit between said casing and said frame by movement of the casing into the frame. 80

2. A cabinet comprising a frame, a casing for engagement within said frame, and means to produce a tight fit between said casing and said frame by movement of the casing into the frame, irrespective of variation in size within predetermined limits between said casing and said frame. 90

3. A cabinet comprising a frame element and a casing element for engagement within said frame element, at least one of said elements having a rearwardly and inwardly directed surface adapted to be engaged by the other element to produce a tight fit between said elements. 95

4. A cabinet comprising a frame, a casing for engagement within said frame, rearwardly and inwardly directed surfaces on said frame and casing, respectively, coacting to produce a tight fit between said casing and said frame by movement of the casing into the frame, and means for securing said casing to said frame. 100

5. A cabinet comprising a frame, a casing for engagement within said frame, means to produce a tight fit between said casing and said frame by movement of the casing into the frame, irrespective of variations in size within predetermined limits between said casing and said frame, and means for securing said casing to said frame. 110

6. A cabinet comprising a frame element and a casing element for engagement with said frame element, at least one of said elements having a rearwardly and inwardly directed surface adapted to be engaged by the other element to produce a tight fit between said elements, and means for securing said casing element to said frame element. 120

7. A cabinet comprising a frame element, means for permanently and rigidly securing said frame element to a wall, and a casing element adapted for engagement within said frame element, said frame and casing elements having coacting parts to assure a tight fit of said casing element within said frame. 130

element, irrespective of variations in the size of said elements within predetermined limits.

8. A cabinet comprising a sheet metal frame element having in cross-section right angularly disposed portions and a connecting portion extending obtusely with respect to said right angularly disposed portion, and a casing for engagement within said frame inclusive of a marginal portion for contact with the obtusely extending connecting portion of said frame.

9. A cabinet comprising a sheet metal frame element having in cross-section right angularly disposed portions and a connecting portion extending obtusely with respect to said right angularly disposed portions, a casing for engagement within said frame inclusive of a marginal portion for contact with the obtusely extending connecting portion of said frame, a tongue struck from said obtusely extending connecting portion and a fastener passed through said casing and engaged with said tongue.

10. In a cabinet, a sheet metal frame having in cross-section a front portion and a rearwardly extending portion disposed at an obtuse angle to said front portion.

11. In a cabinet, a sheet metal frame having in cross-section a front portion, a rearwardly extending portion disposed at an obtuse angle to said front portion, and a fastener receiving tongue struck from said rearwardly extending portion.

12. In a cabinet, a sheet metal frame having in cross-section a front portion, a rearwardly extending portion disposed at an obtuse angle to said front portion, and a fastener receiving tongue struck from said rearwardly extending portion and disposed at right angles to said front portion.

13. In a wall cabinet a sheet metal frame having in cross-section front and side portions disposed in right angular relation to one another and terminating in marginal portions disposed respectively at acute angles to said front and side portions for interlocking engagement with a frame anchoring device.

14. In a wall cabinet a sheet metal frame having in cross-section front and side portions disposed in right angular relation to one another and terminating in marginal portions disposed respectively at acute angles to said front and side portions for interlocking engagement with a frame anchoring device, a portion disposed at obtuse angles to said front and said side portions and connecting them, a tongue extending from said connecting portions parallel to said side portion, a casing for engagement within said frame, and a fastener adapted to be passed through said casing and engaged with said tongue.

15. In a cabinet a frame and a sheet metal casing for engagement within said frame, said casing in cross-section being inclusive of

a side wall and having a laterally outwardly extending front wall terminating in an inwardly directed marginal portion disposed at an acute angle to said front wall for engagement with said frame.

In testimony whereof I hereunto affix my signature.

GLENN T. GOURLEY.
